TRI-COLOR KINESCOPE BEAM CONVERGENCE SYSTEM

Hunter C. Goodrich, Collingswood, N. J., assignor to Radio Corporation of America, a corporation of Delaware

Application May 28, 1953, Serial No. 357,956

4 Claims. (Cl. 315—13)

This invention relates to systems for controlling the electron beams of cathode ray tubes and particularly to systems in which a plurality of beams is deflected by a common deflection apparatus.

One type of cathode ray tube with which the present invention may be successfully employed is a color kinescope of the general type described in an article titled "A three-gun shadow-mask color kinescope," by H. B. Law, published in the Proceedings of the I. R. E., vol. 39, No. 10, October 1951, at page 1186. Such a tube forms the subject matter of Patent No. 2,595,548, issued May 6, 1952, to Alfred C. Schroeder, and titled Picture Reproducing Apparatus. Such a tube has a luminescent screen as part of a target electrode in which different phosphor areas produce differently colored light when excited by electron beam components impinging upon it from different angles, the angle of impingement determining the particular color of the light produced by the phosphor areas. The invention also pertains to a kinescope of the type described in another article titled "A one-gun shadow-mask color kinescope," by R. R. Law, published in the Proceedings of the I. R. E., vol. 39, No. 10, October 1951, at page 1194. Such a tube is the subject matter of a copending U. S. patent application of Russell R. Law, Serial No. 165,553, filed June 1, 1950, and titled Color Television.

It is necessary for the satisfactory operation of such kinescopes to effect substantial convergence of the different electron beam components at all points of the raster scanned thereby at the target electrode. In general, this convergence may be effected by means of apparatus such as that disclosed in an article titled "Deflection and convergence in color kinescopes," by A. W. Friend, published in the Proceedings of the I. R. E., vol. 39, No. 10, October 1951, at page 1249. One such system in accordance with the disclosure of this article forms the subject matter of a copending application of Albert W. Friend, Serial No. 164,444, filed May 26, 1950, now Patent No. 2,751,519, granted June 19, 1956, and titled Electron Beam Controlling System. Such beam convergence apparatus includes an electron-optical system by which to control the beam convergence angles. The electron-optical system is variably energized as a function of the radial angle of beam deflection.

Another type of apparatus for controlling the convergence of a plurality of electron beam components in a predetermined plane and with which the present invention is more particularly concerned comprises, in general, a means for producing a plurality of electron beam components which traverse pre-deflection paths that are spaced respectively about the longitudinal axis of the tube, and individual electromagnetic means located respectively adjacent to the pre-deflection beam paths and of such a character to be energizable directly from the beam deflection circuits in a manner to effect the desired beam convergence. In this manner, the beam convergence angle may be varied in a manner suitable to maintain the

2

desired beam convergence in the predetermined plane at all points in the raster scanned at the target electrode.

More particularly, it will be understood that the term "beam components" as used in this specification and in 5 the appended claims denotes either a plurality of individual electron beams emanating, respectively, from a plurality of electron guns or from a single electron gun provided with suitable electron-optical, or other apparatus, for forming three individual beams and, in addition, 10 those components of a single electron beam to which is imparted a spinning motion so as to trace a substantially conic locus at different positions thereof. Accordingly, the apparatus by which a plurality of such electron beam components is produced may include on the one hand, three electron guns or, on the other hand, a single electron gun, together with the auxiliary apparatus by which the spinning motion is imparted to the beam.

The particular beam convergence electromagnetic apparatus to which this invention pertains includes for each 15 beam component a pair of pole pieces located internally of the kinescope envelope. It has been found that magnetic flux leaking from the deflection yoke traverses the various pairs of pole pieces differently, thereby tending to cause a misconvergence of the beam components.

20 It, therefore, is an object of the present invention to prevent leakage flux from a raster-scanning deflection yoke from affecting individual beam-convergence electromagnets in a manner to cause misconvergence of a plurality of beam components.

25 Another object of the invention is to counteract the misconverging effect of leakage flux from the beam deflection apparatus by suitable energization of the beam convergence electromagnets.

In accordance with the invention, multi-beam cathode 30 ray tube apparatus, having a plurality of beam convergence electromagnets located in a pre-deflection region of the beams, is provided with an energizing system for the electromagnets by which all of the electromagnets are similarly energized as a function of the raster-scanning beam deflection angle, and by which predetermined ones 35 of the electromagnets are dissimilarly energized as a function of the raster-scanning beam deflection angle in such a manner as to counteract the misconverging effect of flux leakage from the beam deflection apparatus into 40 the beam convergence region including the electromagnets.

45 The novel features that are considered characteristic of this invention are set forth with particularity in the appended claims. The invention itself, however, both as to its organization and method of operation, as well as additional objects and advantages thereof, will best be understood from the following description when read in conjunction with the accompanying drawings.

In the drawings:

50 Figure 1 is a view showing the general arrangement of image-reproducing apparatus embodying one form of an electron beam convergence system in accordance with this invention;

55 Figure 2 is a transverse cross-sectional view taken generally on the line 2—2 of Figure 1 and showing the arrangement of the beam convergence electromagnets; and,

60 Figure 3 is a schematic circuit diagram of an arrangement in accordance with the invention for energizing the electromagnetic beam convergence apparatus.

65 Reference first will be made to Figure 1 for a general description of an illustrative embodiment of electron beam convergence system in accordance with the present invention. The system includes a tri-color kinescope 11 which may be of the same general type as that disclosed in the H. B. Law paper previously referred to. It will be understood, however, that the kinescope, alternatively, may be of other types such as that shown in the R. R. Law paper.

In either case, however, the kinescope preferably has a substantially flat luminescent screen 12 provided with a multiplicity of small phosphor areas arranged in groups and capable respectively of producing light of the different primary colors in which the image is to be reproduced when excited by an electron beam. In back of and spaced from the screen 12 there is an apertured masking electrode 13 having an aperture for and in alignment with each group of phosphor areas of the screen 12.

In the particular tube illustrated, the kinescope also has a plurality of electron guns, equal in number to the number of primary colors in which the image is to be reproduced. Each of these guns may be conventional, consisting of a cathode, a control grid and a focussing electrode. Since the three guns are identical, the different parts thereof will be referred to collectively as the cathodes 14, the control grids 15, and the focussing electrodes 16. The three electron guns produce schematically represented beams 17, 18 and 19 by which to energize, respectively, the blue, red and green phosphor areas of the screen 12. When these electron beams are properly converged in the plane of the masking electrode 13 they pass through the apertures thereof from different directions and impinge upon different phosphor areas of the various groups so as to produce blue, red and green light. It is to be noted that the size of the phosphor areas, the angles between the beams and the spacing of the mask 13 from the screen 12 as compared with the length of the tube are exaggerated for better illustration of the operation of the kinescope.

The electron-optical apparatus of the kinescope 11 also includes a beam-accelerating electrode consisting, in the present instance, of a conductive wall coating 20 formed on the inner surface of the tubular glass neck 21 of the kinescope extending from the region adjacent to the outer end of the focusing electrodes 16 to the conical section 22 of the tube which in this case is metallic. Suitable electrical connection (not shown) is made at the junction of the wall coating with the metal cone 22. Preferably, the target electrode structure, including the masking electrode 13 and the luminescent screen 12 which for this purpose may be metallized, is electrically connected to the metal cone 22 by suitable means (not shown). Metallization of a luminescent screen of the character described may be effected in the manner disclosed in a paper by D. W. Epstein and and L. Pensak titled "Improved cathode ray tubes with metal-backed luminescent screens," published in the RCA review, vol. VII, March 1946, at pages 5-10.

The described electrode structure of the kinescope may be energized in a conventional manner such as that illustrated. The source of energy is represented by a battery 23 across the terminals of which there is connected a voltage divider 24. The cathodes 14 are connected to the grounded point of the voltage divider and the control grids 15 are connected to a point which is somewhat negative relative to ground. Similarly, the focussing electrodes 16 are connected to a point on the voltage divider which may conventionally be at a potential of approximately 3000 volts positive relative to the grounded cathodes. Also the beam-accelerating anode, including the wall coating 20 and metal cone 22, is connected to the voltage divider 24 at a point which may conventionally be approximately 18,000 volts positive relative to the grounded cathodes.

The electron beams 17, 18 and 19 are modulated suitably in intensity under the control of color-representative video signals derived from a source 25. It will be understood that the video signal source is represented herein entirely diagrammatically since it does not form an essential part of the present invention. The signal source 25 usually will be part of a signal receiver and may be understood to include a signal detector, or equivalent device, together with one or more stages of video signal amplification. Alternatively, the video signal source may be a

color television camera in the event that the kinescope 11 is employed as a monitor, for example. Also, it will be understood that the illustrated connection of the video signal source 25 to the electron guns of the kinescope 11 is merely diagrammatic and accordingly these connections may or may not be made directly to the cathodes 14. Instead, it will be understood that they may be made to the grids 15 or, in accordance with some modes of operation of color image-reproducing apparatus, the video signal source may be connected both to the cathodes and to the control grids of the electron guns.

Also associated with the color kinescope 11 is a deflection yoke 26 which may be entirely conventional including two pairs of suitably placed coils electrically connected together in such a manner that, when properly energized, electromagnetic fields are produced, whereby to effect both horizontal and vertical angular deflections of the electron beams so as to scan the usual rectangular raster. Energization of the deflection coils comprising the yoke 26 may be effected by conventional vertical and horizontal deflection wave generators 27 and 28, respectively (see Figure 3). Such apparatus will be understood to function suitably to produce substantially sawtooth energy at both horizontal and vertical deflection frequencies so that the fields produced by the yoke 26 are varied in a substantially sawtooth manner.

The beam convergence system, in accordance with the present invention, also includes a plurality of electromagnetic field producing elements such as the magnets 29 and 30 mounted around the neck 21 of the color kinescope adjacent to the pre-deflection paths of the electron beam components. It is to be understood that the precise location of these magnets is not necessarily indicated in this figure. Instead, as will appear in greater detail from a subsequent portion of the specification, it is to be understood that each of these magnets is located relative to one of the electron beam components so as to influence its associated beam component to the substantial exclusion of the others. Furthermore, it is to be understood that these magnets are of a character which, when suitably energized, produce respective fields which are transverse to the associated beam paths.

Each of these convergence electromagnets includes a pair of spaced pole pieces and at least one energizing winding. Preferably two windings are provided for each of the electromagnets for separate energization. In addition, predetermined ones of the electromagnets are provided, respectively, with third windings in accordance with this invention. These features will be described subsequently in greater detail.

Before describing the details of the convergence system with which the present invention is related, a brief description will be given of the general manner in which the apparatus functions to produce the desired results. The convergence magnets such as 29 and 30 are energized by substantially unidirectional energy so as to effect an initial convergence of the electron beam components substantially in the plane of the apertured masking electrode 13. In order to do this, the unidirectional energization of these magnets is effected in such a way that the magnets may be individually energized in different magnitudes. In effecting this initial beam convergence, it is to be understood that the beams may be in any desired one of their different deflected positions. For example, they may be initially converged at the center of the raster to be scanned. Alternatively, they may be initially converged at one corner of the raster.

The convergence magnets such as 29 and 30 also are dynamically energized by the control wave energy derived from a suitable generator (not shown in Figure 1) so as to effect a variation in the magnitude of the transverse fields produced respectively thereby. These field strength variations are in accordance with a predetermined function of the beam deflection. Variations in the

strength of the fields produced by the convergence magnets such as 29 and 30 effect corresponding variations in the paths of the electron beam components relative to the longitudinal axis of the tube. Hence, suitable variations are made in the convergence angles between the various beam components so as to produce the desired convergence of the beam components substantially in the plane of the masking electrode 13.

For a further description of this type of beam convergence apparatus, reference now will be made to Figure 2 of the drawings. This figure shows more clearly the relative positions of the convergence magnets, such as 29 and 30 and, additionally, 31, relative to one another and to the electron beams with which they are respectively associated. Inasmuch as all of these magnets are substantially the same, only one of them will be described in detail. The convergence magnet 29, which is associated with the blue electron beam 17, is provided with a core having a body portion 32 and two external pole pieces 33 and 34. These pole pieces are mounted so as to be in close association with the tube neck 21. Also, as indicated in Figure 1, the pole pieces extend for some distance longitudinally of the tube substantially as indicated. The magnet also is provided with an energizing coil structure 35 mounted upon the body portion 32. The energizing coil 35 preferably is provided with two windings, one for static energization and the other for dynamic energization in a manner to be described subsequently. Also, in accordance with this invention, the coils of magnets 30 and 31 have third windings. The convergence magnet 29 produces a field which, in the vicinity of the electron beam 17, is substantially transverse to the axis of the kinescope. By means of such a field, the electron beam 17 may be moved toward or away from the longitudinal tube axis. The direction and magnitude of such a beam movement is controlled by the energization of the magnet by means including the coil 35.

In Figure 2, it also is illustrated that for each of the magnets there are provided on the inside of the tube neck 21 extended pole pieces so as to increase the effectiveness of these magnets. The magnet 29, for example, is provided with a pair of inwardly extending pole pieces 36 and 37, associated respectively with the external pole pieces 33 and 34. By such means, it is seen that the reluctance of the magnetic circuit is considerably decreased, and also the flux distribution of the field produced between the internal pole pieces 45 and 46 is considerably improved.

With beam convergence apparatus of this general character, it may be seen from a further consideration of Figure 2 that such apparatus is adversely effected by leakage flux from the deflection yoke. Leakage deflection flux of a character to deflect the electron beam components 17, 18 and 19 to the left as viewed in the drawing is indicated by the broken lines 38. With respect to the internal pole pieces 36 and 37 associated with the electromagnet 29, no adverse effects of the leakage deflection flux are produced. However, it is seen that the leakage deflection flux 38 passes between the internal pole pieces 39 and 40 of the electromagnet 30 substantially at right angles to these pole pieces since this is the path of lowest reluctance. Similarly, the leakage deflection flux 38 passes between the internal pole pieces 41 and 42 of the electromagnet 31 at right angles to these pole pieces. As a result, it may be seen that when the beams are being deflected to the left, the red beam 18 will be moved to a higher position than it would have in the absence of the leakage flux from the deflection yoke, as indicated by the arrow. Similarly, the green beam 19 will have a lower than normal position when beam deflection is toward the left. Conversely, when beam deflection by the yoke is toward the right, as viewed in Figure 2, the leakage flux 38 will be in the opposite

direction, thereby tending to move the red beam downwardly and the green beam upwardly. Consequently, there is effected a misconvergence of the electron beam components as a result of the leakage flux from the deflection yoke traversing the internal pole pieces of certain of the convergence electromagnets.

Reference now will be made to Figure 3 of the drawings for a general description of an illustrative manner in which the beam convergence apparatus may be energized. The energizing coils of the convergence magnets 29, 30 and 31 include dynamic windings 43, 44 and 45 respectively. These convergence magnets also include static windings 46, 47 and 48, respectively. The energizing circuit for the static convergence windings 43, 44 and 45 includes a series circuit of resistors 49, 50 and 51 connected between the positive terminal of a power supply and its load. Preferably, these resistors are adjustable so as to enable the individual control of the energizing current for the associated static windings of the convergence magnets 29, 30 and 31, respectively.

The dynamic windings 43, 44 and 45 of the convergence magnets 29, 30 and 31, respectively, are connected in series with one another and to vertical and horizontal convergence wave generators 52 and 53, respectively. These convergence wave generators may be of the general type disclosed in the I. R. E. Friend paper or any other suitable forms. In general, the substantially sawtooth wave energy 54 of field frequency which is derived from a conventional vertical deflection wave generator 27 for energization of the vertical deflection coils 55 is converted by means of the vertical convergence wave generator 52 into a substantially parabolic wave 56. This parabolic wave energy is coupled by a capacitor 57 to the series connection of the dynamic windings of the convergence electromagnets. In a substantially similar manner, the line frequency sawtooth wave energy 58 derived from the horizontal deflection wave generator 28 for the energization of the horizontal deflection yoke windings 59 is converted by the horizontal convergence wave generator 53 to substantially parabolic wave 60 for impression by means including a coupling capacitor 61 upon the dynamic windings of the beam convergence electromagnets 29, 30 and 31. By such means, it is seen that all of the convergence magnets are similarly energized dynamically as functions of both vertical and horizontal beam deflection angles so as to effect substantial convergence of the electron beam components in the plane of the target electrode structure at all points in the scanned raster.

In accordance with the present invention, predetermined ones of the convergence electromagnets are provided with additional windings as part of the energizing means by which the misconverging effect of the leakage flux from the deflection yoke is counteracted. In the particular illustrative example of the invention disclosed in the drawings, the electromagnets 30 and 31 are provided with these additional windings since these are the electromagnets, the operation of which is adversely affected by the leakage flux. In Figure 3, the electromagnets 30 and 31 are provided respectively with additional leakage flux counteracting windings 62 and 63, respectively. These windings are connected in series with one another and also in series with the horizontal yoke windings 59. Accordingly, the leakage flux counteracting windings 62 and 63 are traversed by the substantially sawtooth current wave 58 at horizontal deflection frequency.

It is to be noted, however, that the windings 62 and 63 are wound on their respective electromagnets 30 and 31, or are connected in the energizing circuit, in such a way as to produce in the respective pole piece gaps field components of opposite polarity. The reason for this may be seen by again referring to Figure 2. In order to counteract the adverse effect of the leakage flux between the pole pieces 39 and 40 of the electromagnet 30, it is

necessary to produce a field component of such a character as to move the red beam 18 radially outward from the longitudinal axis of the tube. In order to counteract the effect of the same flux in the gap between the pole pieces 41 and 42 of the electromagnet 31, it is necessary that the additional field component be of such a character as to move the green electron beam 19 radially inward toward the longitudinal axis of the kinescope. It, thus, is seen that the leakage deflection flux is counteracted by dissimilarly energizing predetermined ones of the convergence electromagnets as a function of the beam deflection angle.

The particular illustrative embodiment of the invention discloses the provision of a counteracting field component as a function of the horizontal beam deflection angle. It is to be understood that, should the vertical deflection flux leakage into the beam convergence region cause objectionable misconvergence of the beams, the convergence electromagnets may be additionally energized as a function of the vertical beam deflection.

It may be seen, therefore, from the foregoing description of an illustrative embodiment of the present invention that there is provided a means for counteracting the leakage flux from a raster scanning deflection yoke which tends to influence the beam convergence apparatus adversely to produce objectionable misconvergence of the beams. The system for accomplishing this is relatively simple and effective in accordance with the present invention, consisting essentially in the dynamic energization of predetermined ones of a plurality of convergence electromagnets as a function of the beam deflection angle.

The invention, having been illustratively disclosed, is defined in the appended claims.

What is claimed is:

1. In a cathode ray tube image-reproducing system wherein a plurality of electron beam components, which traverse predeflection paths that are spaced respectively about the longitudinal axis of the tube, are angularly deflected both horizontally and vertically by electromagnetic beam deflection apparatus to scan a raster at a target electrode, electron beam convergence apparatus comprising: a plurality of electromagnets respectively mounted adjacent to said predeflection beam paths and energizable to produce respective fields transverse to said beam paths, each of said electromagnets having a pair of pole pieces located internally of said tube and respectively extending into the region of said associated beam component; means developing correction wave energy varying in magnitude continuously during the entire raster-scanning period as a function of said raster-scanning beam deflection angle; and means energizing predetermined ones of said electromagnets by said correction wave energy in such a manner as to produce transverse field components of opposite polarity in respective ones of said predetermined electromagnets, whereby to counteract the misconverging effect of flux leakage from said beam deflection apparatus to said predetermined electromagnets.

2. In a cathode ray tube image-reproducing system wherein a plurality of electron beam components, which traverse predeflection paths that are spaced respectively about the longitudinal axis of the tube, are angularly deflected both horizontally and vertically by electromagnetic beam deflection apparatus to scan a raster at a target electrode, electron beam convergence apparatus comprising: a plurality of electromagnets respectively mounted adjacent to said predeflection beam paths and energizable to produce respective fields transverse to said beam paths, each of said electromagnets having a pair of pole pieces located internally of said tube and respectively extending into the region of said associated beam component; means developing convergence wave energy varying in magnitude as a function of said raster-scanning beam deflection angle; means energizing said electromagnets by said convergence wave energy in such a manner as to effect dynamic convergence of said beam components; means developing correction wave energy varying in magnitude continuously during the entire raster-scanning period as a function of said raster-scanning beam deflection angle; and means energizing second and third ones of said electromagnets by said correction wave energy in such a manner as to produce transverse field components of opposite polarity in respective ones of said second and third electromagnets, whereby to counteract the misconverging effect of flux leakage from said beam deflection apparatus to said second and third electromagnets.

3. In a cathode ray tube image-reproducing system wherein a plurality of electron beam components, which traverse predeflection paths that are spaced respectively about the longitudinal axis of the tube, are angularly deflected both horizontally and vertically by electromagnetic beam deflection apparatus to scan a raster at a target electrode, electron beam convergence apparatus comprising: a plurality of electromagnets respectively mounted adjacent to said predeflection beam paths and energizable to produce respective fields transverse to said beam paths, each of said electromagnets having a pair of pole pieces located internally of said tube and respectively extending into the region of said associated beam component; means developing substantially parabolic convergence wave energy varying in magnitude as a function of said raster-scanning beam deflection angle; means energizing said electromagnets by said convergence wave energy in such a manner as to effect dynamic convergence of said beam components; means developing substantially sawtooth correction wave energy varying in magnitude continuously during the entire raster-scanning period as a function of said raster-scanning beam deflection angle; and means energizing predetermined ones of said electromagnets by said correction wave energy in such a manner as to produce transverse field components of opposite polarity in respective ones of said predetermined electromagnets, whereby to counteract the misconverging effect of flux leakage from said beam deflection apparatus to said predetermined electromagnets.

4. In a cathode ray tube image-reproducing system wherein three electron beam components, which traverse predeflection paths that are symmetrically spaced respectively about the longitudinal axis of the tube, and angularly deflected both horizontally and vertically by electromagnetic beam deflection apparatus to scan a raster at a target electrode, electron beam convergence apparatus comprising: three electromagnets respectively mounted adjacent to said predeflection beam paths and energizable to produce respective fields transverse to said beam paths, each of said electromagnets having a core including a body portion located externally of said tube and a pair of pole pieces located internally of said tube and respectively extending from points adjacent to opposite ends of said body portion into the region of said associated beam component, the pole pieces of a first one of said electromagnets extending substantially parallel to leakage flux from said beam deflection apparatus; means developing convergence wave energy varying in magnitude as a function of said raster-scanning beam deflection angle; means energizing all of said electromagnets substantially similarly by said convergence wave energy in such a manner as to effect dynamic convergence of said beam components; means developing correction wave energy varying in magnitude continuously during the entire raster-scanning period as a function of said raster-scanning beam deflection angle; and means energizing second and third ones of said electromagnets by said correction wave energy in such a manner as to produce transverse field components of opposite polarity in respective ones of said second and third electromagnets, whereby to counteract the misconverging effect of flux leakage from said beam deflection apparatus to said second and third electromagnets.

5. In a cathode ray tube image-reproducing system wherein a plurality of electron beam components, which traverse predeflection paths that are spaced respectively about the longitudinal axis of the tube, are angularly deflected both horizontally and vertically by electromagnetic beam deflection apparatus to scan a raster at a target electrode, electron beam convergence apparatus comprising: a plurality of electromagnets respectively mounted adjacent to said predeflection beam paths and energizable to produce respective fields transverse to said beam paths, each of said electromagnets having a pair of pole pieces located internally of said tube and respectively extending into the region of said associated beam component; means developing convergence wave energy varying in magnitude as a function of said raster-scanning beam deflection angle; means energizing said electromagnets by said convergence wave energy in such a manner as to effect dynamic convergence of said beam components; means developing correction wave energy varying in magnitude continuously during the entire raster-scanning period as a function of said raster-scanning beam deflection angle; and means energizing second and third ones of said electromagnets by said correction wave energy in such a manner as to produce transverse field components of opposite polarity in respective ones of said second and third electromagnets, whereby to counteract the misconverging effect of flux leakage from said beam deflection apparatus to said second and third electromagnets.
